UNITED STATES PATENT OFFICE.

ALBERT S. MACK, OF KLAMATH FALLS, OREGON.

ELECTRICAL HEATER.

1,141,197.

Specification of Letters Patent.

Patented June 1, 1915.

Application filed October 28, 1914. Serial No. 869,292.

To all whom it may concern:

Be it known that I, ALBERT S. MACK, a citizen of the United States, residing at Klamath Falls, in the county of Klamath and State of Oregon, have invented certain new and useful Improvements in Electrical Heaters, of which the following is a specification, reference being had to the accompanying drawings.

This invention relates to an improved electrical heater and has for its primary object to provide a device of this character for quickly heating water or other fluids which is so constructed that the heating element may be readily removed for the purpose of repair when necessary without cutting off or diminishing the flow of water.

The invention has for a further object to provide an electrical heater embodying in its essential features an elongated cylindrical metal tube, an electrical heating coil extending substantially the entire length of said tube, and an interior asbestos packing for said coil arranged within the tube.

The invention has for an additional object to produce a device of the above character which is exceedingly simple in its construction, capable of manufacture at comparatively small cost, and highly efficient and serviceable in practical use.

With the above and other objects in view, my invention consists in the novel features of construction, combination, and arrangement of parts to be hereinafter more fully described, claimed, and illustrated in the accompanying drawing, in which,

Figure 1 is a side elevation of a water heater embodying the present invention; Fig. 2 is an enlarged longitudinal section, parts of the device being broken away; and Fig. 3 is a section taken on the line 3-3 of Fig. 2.

Referring in detail to the drawing, 5 and 6 indicate the outlet and inlet pipes, respectively, which are connected to a suitable water tank or reservoir, (not shown). The pipe 6 is connected to the cold water supply pipe 7 by means of a suitable T-coupling 8. In one end of this coupling a nipple 9 is threaded, and to said nipple the cap member 10 is detachably threaded or otherwise connected. This cap is interiorly threaded to receive one end of a long galvanized iron pipe 11. Adjacent to its opposite end this pipe is provided with an opening 12 with which the bore of the cut-

let pipe 5 leading to the water tank is adapted to register. This inlet pipe is held in connection with the pipe 11 by means of a T-coupling 13 which is interiorly threaded and projects a slight distance beyond the end of said pipe 11, as clearly shown in Fig. 2. In one end of the coupling 13, a collar indicated at 14 is removably threaded, said collar when in position being spaced from the end of the coupling so that a sleeve 15 may also be threaded thereon for a purpose which will appear from the following description.

16 designates an elongated cylindrical nickel plated tube which is arranged within the pipe 11 in spaced relation to the walls thereof. The lower end of this tube is closed while its upper end is formed with an outwardly projecting annular flange or washer plate 17 designed to seat upon the upper edge of the collar 14. The sleeve 15 is adapted to be threaded within the upper end of the coupling member 13 into clamping engagement upon the edge of this flange. A solid asbestos packing 18 snugly fits within the tube 16 and the upper end of said jacket is diametrically enlarged as at 19 to extend outwardly over the flange 17 and fit within the sleeve 15. A centrally disposed longitudinally extending rod or core 20 is arranged within the jacket 18 and to the lower end of said rod one end of a long wire coil 21 is secured by means of the screw indicated at 22. The coils of this wire are suitably spaced and to the upper end thereof a wire 21' is connected which leads out through an insulating bushing 24 threaded in a metal cap 25 which is removably engaged upon the sleeve 15.

26 designates the current supply wire which also extends through the insulating bushing 24 and is connected to the upper end of the metal core 20. A resistance wire 27 is included in the circuit, said wire being connected to the coil 21 at the desired point. It will be understood that a suitable switch is arranged in the circuit so that the resistance wire may be cut out in order to reduce the heating capacity of the coil. When the wire 27 is in the circuit, the coil 21 from the point of connection of said wire therewith to the end of the wire 26, will be dead, the circuit being closed through the wire 27 and the remaining portion of the coil and thus generating a relatively high degree of heat. When the wire 26 is

connected in the circuit, said circuit is lengthened so as to carry less amperage and thereby produce a less degree of heat.

From the above description, it will be understood that when the current is turned on, the wire coil 21 becomes highly heated, and such heat is transmitted through the nickel plated tube or shell 16 to the water which surrounds the same. There is a constant circulation through the pipe 11 upwardly from the inlet pipe 6, to the outlet pipe 5 and back to the tank. Cold water is initially supplied to the tank through the pipe 7. By reason of the great length of the wire coil, and the rapid circulation of the water which is in close proximity to the coil, overheating and breaking of the coil is prevented, as the temperature thereof is reasonably low. If, however, experience should prove that the coils are breaking down from overheating, they could be placed farther apart by making the coils of larger diameter or the heating tube 16 could be made longer. It will be apparent that by means of the arrangement of parts above described, the water will be quickly heated in its passage through the pipe 11 and the expense incident to such heating reduced to a minimum. It will be noted that there are only two turns in the water circuit from the time the water leaves the tank until it is returned thereto, thus avoiding friction and giving freer circulation to the water.

From the foregoing description, taken in connection with the accompanying drawing, the construction, manner of operation, and several advantages of my invention will be clearly and fully understood. The device, while exceedingly simple in construction, is also very convenient and serviceable in practical use. By mounting the coil within the pipe 11 in the manner shown, it will be observed that the same can be readily removed therefrom by the removal of the cap member 25 and sleeve 15, without cutting off or diminishing the supply of water. The several parts of the invention may be readily set up in condition for use without requiring the services of an expert mechanic. It will further be understood that the invention may be produced in various forms and proportions other than that shown in the drawing as may be necessitated by the particular circumstances of each individual case.

While I have shown and described the preferred form and construction of the several elements employed, it is manifest that the device may be greatly modified in various parts, and I therefore reserve the privilege of resorting to all such legitimate changes therein as may be fairly embodied within the spirit and scope of the invention as claimed.

Having thus fully described my invention, what I desire to claim and secure by Letters Patent, is:—

1. An electrical heating device of the character described including an outer elongated metal shell, inlet and outlet pipes connected to the lower and upper ends of said shell, a relatively thin inner metal shell arranged in spaced concentric relation to the outer shell and substantially co-extensive in length therewith, said inner shell being open at one end and having an outwardly projecting flange, an interiorly threaded coupling member connecting said outer shell to the outlet pipe, a collar threaded in said coupling upon which said flange rests, a sleeve threaded in said coupling member and engaged upon the flange on said inner shell, an asbestos packing snugly fitting within said inner shell and having an enlarged end disposed within said sleeve, an electric heating coil arranged within said packing and extending the entire length thereof, and a removable cap threaded upon said sleeve to retain said inner shell and the packing within said outer shell. 70 75 80 85 90

2. An electrical heating device of the character described including an outer shell, a relatively thin inner metallic shell disposed in spaced relation to the outer shell and open at its upper end, a solid mass of non-conducting material entirely filling said inner shell and projecting beyond the open end thereof, means for removably retaining said non-conducting material within the inner shell and also holding said inner shell against movement with respect to the outer shell, and a wire heating coil extending through said mass of non-conducting material, the turns of said coil being held in 100 105 definite spaced relation to each other by the material. 95

3. An electrical heating device of the character described including an outer shell, an inner metallic shell spaced from said outer shell and open at its upper end, a solid mass of non-conducting material entirely filling said inner shell and having an enlarged upper end portion approximately equal to the internal diameter of the outer shell, means 110 115 detachably mounted upon the outer shell to removably retain the non-conducting material within said inner shell, and an electric heating coil extending through said mass of non-conducting material and entirely 120 confined within the same. 125

4. An electrical heating device of the character described including an outer cylindrical shell, a relatively thin inner metallic shell spaced from said outer shell, inlet and outlet pipes detachably connected to the opposite ends of said outer shell, a solid mass of non-conducting material entirely filling said inner shell and extending above the upper end thereof, means removably 130

mounted upon the connection between the outlet pipe and the outer shell to hold the inner shell and the packing against relative movement and also with respect to said outer shell, and an electric heating coil extending through said mass of material, the turns of said coil being held in definite spaced relation by the material.

5. An electrical heating device of the character described including an outer cylindrical shell, a relatively thin inner metallic shell spaced from the outer shell and having an upper open end provided with an outwardly extending flange, outlet and inlet pipes connected to the upper and lower ends respectively of said outer shell, a solid mass of non-conducting material entirely

filling the inner shell and having an enlarged upper end portion resting upon said flange, means removably mounted upon the upper end of said outer shell to removably hold said inner shell and the packing in place and prevent movement of the same with respect to said outer shell, and an electric heating coil having its turns embedded within said non-conducting material and held in definite spaced relation thereby.

In testimony whereof I hereunto affix my signature in the presence of two witnesses.

ALBERT S. MACK.
